UNITED STATES PATENT OFFICE.

SAMUEL F. BASHARA AND JOSEPH F. BASHARA, OF HOUSTON, TEXAS.

DRILL BIT.

Application filed February 16, 1920. Serial No. 359,131.

To all whom it may concern:

Be it known that we, SAMUEL F. BASHARA and JOSEPH F. BASHARA, citizens of the United States and Mount Lebanon, Syria, respectively, residing at Houston, in the county of Harris and State of Texas, have invented certain new and useful Improvements in a Drill Bit, of which the following is a specification.

10 This invention relates to new and useful improvements in a drill bit.

One object of the invention is to provide a drill bit of the fish tail type, which is adapted to be attached to the lower end of 15 a drill stem to be used in rotary drilling.

The fish tail bit now in common use is formed of relatively thin material and has thin cutting blades which soon become worn off, and dulled, or broken and must be 20 withdrawn and sharpened and then again attached to the drill stem and let down into the bore to resume operations. In sharpening the bit, it is often not properly tempered so that the blades readily break and the 25 shank, the most expensive part of the bit, must be thrown away. At the same time, much valuable time is wasted in withdrawing the stem and removing and replacing the bit. It is an object of this invention to 30 provide a drill bit which is relatively thick and which is formed with thick sturdy blades that can not be broken and that will remain sharp for a considerable length of time so that it will not be necessary to pull 35 the stem and substitute a new bit for an old one nearly so often as is the case with fish tail bits now in common use.

Another object of the invention is to provide a drill bit of the type described having 40 a plurality of water courses therethrough, through which water is forced, with great pressure, to the tip of the bit which keeps the bit from becoming too hot and at the same time washes away the gumbo and other 45 cuttings and prevents the same from sticking to the bit.

A still further feature of the invention is to provide a drill bit which is attached directly to the stem through the medium 50 of a heavy drill collar, said bit being formed with cutting blades which will penetrate the formation at an even and uniform rate and which will therefore subject the stem to an even and uniform strain, thus eliminating 55 the liability of the stem becoming twisted in two and the hole lost.

A still further feature of the invention resides in the provision of a sample taking device to be used in connection with the bit herein described.

With the above and other objects in view, the invention has particular relation to certain novel features of construction, operation and arrangement of parts, an example of which is given in the specification and 60 illustrated in the accompanying drawings wherein—

Figure 1 is a side elevation of the bit,

Figure 2 is a vertical sectional view 70 thereof,

Figure 3 is a perspective view,

Figure 4 shows a transverse sectional view taken on the line 4, 4 of Figure 2,

Figure 5 is a side elevation of the bit, showing the sample taking device in connection therewith,

Figure 6 is a vertical sectional view 75 thereof,

Figure 7 shows an enlarged side elevation 80 of a pilot bit employed,

Figure 8 shows a bottom plan view of said 85 pilot bit, and

Figure 9 is a transverse cross section 90 through the bit.

Referring now more particularly to the drawings, wherein like numerals of reference designate similar parts in each of the figures, the numeral 1 refers to the bit, which is formed of relatively thick material, preferably tool steel. The lower end of this 95 bit has the oppositely curved blades or tips 2 which are formed with sharp cutting edges 3. On account of the sturdy design of these blades, the edges will remain sharp for a much longer period of time than is the case 100 with the fish tail bits now in common use, and they will consequently penetrate the various formations encountered readily, thus subjecting the stem to a uniform and even strain and thereby reducing the liability 105 of said stem becoming twisted off, and as they remain sharp for a much longer period of time than is the case with ordinary fish tail bit the stem does not have to be often withdrawn for the sharpening of the bit 110 or the substitution of a new one, and much time is thus saved in the process of drilling. The bit has an outwardly threaded neck 4 which is screwed directly into a heavy drill collar 5 into which the lower end of the drill stem 6 is also threaded. The lower end of the drill collar abuts directly against the

upper smooth face of the bit, thus adding to the strength thereof. In the type shown in Figures 1 to 4, inclusive, the bit has a central fluid conduit 7 which separated into 5 the branches 8, 8 through which water is discharged from the drill stem to the cutting edges 3 and on opposite sides of said central conduit 7 there are the side conduits 9, 9 through which water is discharged from the 10 stem to the sides of the bit. These water conduits are provided to supply a sufficient quantity of water to the bit to keep the same cool and at the same time to disintegrate and carry away all the cuttings and 15 other formation from the point of the bit and prevent said bit from becoming clogged therewith.

In forms shown in Figures 5 to 9, inclusive there is a pilot bit 10 formed of a reduced outwardly threaded neck 11 and oppositely disposed, fan shaped, abrading members 12. This pilot bit is threaded into a centrally located socket in the bit 1 and has a central bore 13 to permit the passage 25 of a core therethrough, and also has water courses through which water is delivered to the abrading surfaces. The bit 1, in this form, also has a central bore 14, which is aligned with the bore 13, the bore through 30 the bit being provided to receive the lower end of the liner 15, whose lower end rests upon, but is not attached to the upper end of the neck 11 of the pilot bit. This liner is formed of two longitudinal sections which 35 are hinged together at one side by means of the hinges 16 and the liner is formed of relatively thin material. This liner projects up into the drill stem as far as desired and it is surrounded and protected by means of a 40 pipe section, whose lower end is screwed into the upper end of the bit 1 and whose upper end is provided with a valve 18 which excludes all water and prevents the same from becoming mingled with the core or 45 sample in said liner, but which permits the escape of air as the core enters the liner.

During the process of drilling the pilot bit 10 cuts around the core, thus leaving a perfect core which passes up into the liner 15, the valve 18 meanwhile opening to permit the escape of air.

When it is desired to examine the sample taken the stem is withdrawn and broken up in the usual way and when the upper end of 55 the pipe section 17 is reached, the valve 18

may be removed and the liner 15 then lifted out and opened, thus leaving the sample in perfect condition unmixed with water or other foreign matter.

As the stem is being withdrawn the valve 60 18 will be seated and the core will be held in the liner by suction.

What we claim is:

1. The combination with a drill bit having a central bore, and whose upper end is 65 formed into a reduced threaded neck and whose lower end has oppositely curved blades, of a pilot drill attached to the lower end of said bit and having a central bore which aligns with the bore of the bit and a 70 tubular liner extending through said bores and whose lower end rests upon the upper end of said drill.

2. The combination with a drill bit having a central bore, and whose upper end is 75 formed into a reduced threaded neck and whose lower end has oppositely curved blades of a pilot drill attached to the lower end of said bit and having a central bore which aligns with the bore of the bit and a 80 tubular liner, formed of sections which are hinged together, said liner extending through said bores.

3. The combination with a drill bit having a central bore, and whose upper end is 85 formed into a reduced threaded neck and whose lower end has oppositely curved blades, of a pilot drill attached to the lower end of said bit and having a central bore which aligns with the bore of the bit, a liner 90 extending through said bores and adapted to receive a core, and a tubular section surrounding the liner and whose lower end is anchored to the drill bit.

4. The combination with a drill bit having a central bore, of a core forming device carried by the lower end of said bit and having a central bore which aligns with the bore of the bit, a liner forming a core barrel within the bore of the drill bit and a tubular section surrounding said core barrel and anchored to the bit.

In testimony whereof we have signed our names to this specification in the presence of two subscribing witnesses.
